Milwaukie, Oreg.

Application July 6, 1954, Serial No. 441,206

5 Claims. (Cl. 144—281)

This invention relates to a hot press machine for laminating relatively thin sheet materials, such as paper and wood veneer, in a continuous ribbon which may be cut to any desired length.

In laminating wood veneers to form plywood and the like, ranging from three-eighths of an inch to an inch or more in thickness, it is customary to glue coat the faces of the veneers, cut them to a predetermined size, and then lay them up loosely in superposed relation in piles comprising the number of veneers desired in the finished panels, such as three, five, seven or more. Each such pile of glue coated veneers is then inserted in one of the inter-platen spaces of a multiple platen hot press. Such a press is adapted to press and cure ten to twenty panels at one time, the press being opened at the termination of the press cycle for removal of all the completed panels and the insertion of a new load of veneer assemblies which have been prepared for the next cycle of operation. This is known as a batch type of operation, and it is used extensively for making rigid panels of standard size which are necessarily limited by the dimensions of the press platens, such as four feet by eight feet. The operation involves a great deal of manual handling of the veneers in laying up the assemblies prior to pressing and also manual handling of the hot panels which must be removed from the press after each cycle of operation. Other disadvantages of the conventional batch process are the loss of heat while the press is open for unloading and loading, the long interval between glue spreading and pressing, limitation of panel size, and the cyclical interruptions to a steady, continuous work flow in the handling of the materials going into the press and the handling of finished panels produced by the press.

Also, the conventional hot press used for laminating is made as rigid as possible, entailing a very expensive type of construction. Ordinarily, the lowermost platen which supplies all the pressure exerted by the press is mounted on a relatively small number of vertical pistons operable in hydraulic cylinders extending down into wells beneath the press. In order to apply uniform pressure over the whole area of the material in the press the lower platen is made of a single rigid steel plate of some thickness backed up by heavy I-beams which transmit and distribute the pressure applied by the hydraulic pistons to the extremities of the platen. This great mass must be lifted each time the press is closed, and a considerable amount of energy is consumed in each cycle of operation in just lifting the movable platens to closed position.

In addition to the numerous disadvantages pointed out, the conventional type of rigid and ponderous movable press platen is found to be unsatisfactory for making relatively thin laminate sheets such as a single layer of wood veneer between two layers of paper. Whereas a press load of veneers, such as are involved in the manufacture of plywood, is sufficiently resilient and compressible to adjust itself readily to small variations in the spacing of the platens, a single thin laminate sheet is incapable of

2

such self-compensation. Regardless of the rigidity of the press and the precision with which the parts are made, there inevitably exists in a press four feet wide and eight feet long a variation in the spacing of the upper and lower platens from point to point which is sufficient to concentrate substantially the entire pressure of the press in certain local areas, leaving other areas substantially without any application of pressure, or, at least, insufficient pressure. Previous attempts to correct the fault by making the movable platen still heavier and more rigid have been unsuccessful because the same defect results from slight variations in the veneer thickness even if the press is geometrically perfect. Conventional hot presses are generally considered to be incapable of laminating thin materials, such as paper and wood veneer, in a three-ply assembly.

The general objects of the present invention are, therefore, to provide a novel form of hot press which will overcome the shortcomings and disadvantages of conventional hot presses in the manufacture of thin laminate sheets.

More specific objects are to provide a hot press which will successfully laminate thin materials in a continuous strip of any desired length, to provide a hot press having a light weight and relatively flexible movable platen, to provide a pneumatically operated hot press, to provide a hot press of the type described having a very brief operating cycle so as not to interpose long delays in the work flow to and from the press, to provide a hot press apparatus which will materially reduce manual handling of the material, to produce a hot press apparatus which is largely automatic and continuous in operation, to provide a control mechanism for hot press apparatus of the type described which will time the press cycle and perform a number of operations in sequence with a minimum of supervision by the operator, and to provide an improved hot press apparatus which is relatively inexpensive to build and economical and reliable in operation.

The present apparatus comprises, in general, a lay-up table, a two-platen hot press, a feed mechanism, a clipper knife and an electric and pneumatic control system. The function of the apparatus is to laminate a single thin layer of wood veneer between two layers of paper, plastic sheet material, metal foil, or any other sheet material capable of being adhesively united with the surfaces of wood veneer. It is not necessary that the same type of sheet material be used on both sides of the veneer, as, for example, when metal foil is applied to one side it is often desirable to have paper applied to the other side. For the purpose of describing the method and apparatus, it will be assumed that the sheet material on both sides of the veneer layer is paper.

The veneer sheets are first coated on both sides with a suitable adhesive and are then laid up edge to edge as core strips between the two paper face sheets which may be fed conveniently from rolls. A length of such assemblage equal to the length of the press is drawn over the lower platen in a feed movement each time the press is opened. During the pressing cycle one of the platens is moved toward the other to press the assemblage and apply the necessary heat to cure the adhesive and form a flat, smooth, flexible, composite sheet. The process is continuous in the sense that a finished portion of the composite sheet is delivered intermittently at short intervals from one side of the press while a length of laid up assembly is continuously being prepared on the other side of the press.

A pair of horizontal feed rolls grip the composite sheet which emerges from the outlet side of the press and draws all the material forward the required distance in each feed movement at the end of a heating cycle. Thus, the alternate operation of the press and feed rolls

discharges a continuous ribbon of the composite sheet which may be split lengthwise into a plurality of ribbons of the desired width. These ribbons are fed through a transverse clipper knife for cutting into the desired lengths. Suitable automatic mechanism is provided for controlling the opening and closing of the press, the length of feed movement, the operation of the clipper knife, and for cycling these operations.

An important feature of the press is the flexible construction of one of the platens which is designed to apply uniform pressure over the whole area of the material which is in contact with the other platen which is rigid. The applied pressure is not affected by irregularities or variations in the thickness of the material which is interposed between the two platens. Preferably, the lower platen is made flexible and upward pressure is applied under the whole area of the lower platen by means of a relatively large number of closely spaced pneumatic diaphragm units which are distributed across the breadth and length of the lower platen.

The foregoing and additional objects and advantages will become apparent as the description proceeds in connection with the accompanying drawings illustrating a preferred embodiment of the invention. It is to be understood, however, that various changes and modifications may be made and certain features may be used without others without departing from the spirit of the invention as defined in the appended claims.

In the drawings:

Figure 1 is a plan view of the apparatus of the invention;

Figure 2 is a side elevation view of the apparatus shown in Figure 1;

Figure 3 is a cross sectional view of the press, taken on the line 3—3 of Figure 2;

Figure 4 is an elevation view of the valve mechanism controlling the movements of the lower platen, taken on the line 4—4 of Figure 2;

Figure 5 is a plan view of the valve mechanism shown in Figure 4;

Figure 6 is a top plan view of the lower platen with portions broken away to illustrate the construction thereof;

Figure 7 is a fragmentary view of the feed switch and clipper switch actuating mechanism, taken on the line 7—7 of Figure 2;

Figure 8 is a sectional view taken on the line 8—8 of Figure 2 showing the longitudinal shearing rolls; and

Figure 9 is a schematic wiring diagram of the control system for the various operating units of the machine.

In Figures 1 and 2, the apparatus is seen to comprise, essentially, a lay-up table A at one side of the press B, a feed roll mechanism C at the other side of the press, and a clipper mechanism D beyond the feed roll. The veneer core strips are laid up by hand on the table A and the assemblage including the face sheets is drawn by the feed roll mechanism C in intermittent step by step movement through the press B. The finished laminate product issues in a continuous ribbon from the feed roll mechanism C until it is cut into the desired lengths by the operation of clipper D.

The table A extends some distance to the left of the portion shown in Figures 1 and 2 and is equipped with a paper roll support (not shown) for feeding a lower sheet of paper 10 in a continuous strip across the surface of the table. Glue coated veneer core strips 11 are placed on the sheet 10, and, as the sheet 10 and core strips 11 are drawn into the press, a top sheet of paper 12 is applied over the assemblage as it is drawn from an upper paper roll 13.

The frame of the press B comprises a pair of longitudinal stringers 15 surmounted by a plurality of transverse I-beams 16. Resting on the transverse I-beams 16 are three longitudinal I-beams 17 supporting a plurality of pneumatic diaphragm units 18. The diaphragm units 18

are equipped with short cylindrical struts or supporting columns 19 for a lower platen 20.

An upper platen 21 is rigidly mounted on a plurality of longitudinal I-beams 22 connected with transverse beams 23, as shown in Figure 3. Transverse beams 23 are supported at their ends on standards 24 which are connected with the lower transverse beams 16. A pair of upper longitudinal frame members 25 interconnect the standards 24 and support a shaft 26 for the upper paper roll 13. The ends of shaft 26 are equipped with sleeve bearings 27 which are adapted to rest on pairs of rollers 28 on the upper frame members 25 to facilitate free turning movement of the paper roll.

The work engaging surface of the lower platen comprises a plurality of long narrow steel plates 30 disposed in edge to edge relation, as shown in Figures 3 and 6. The work engaging surface of the stationary upper platen comprises a plurality of similar plates 31 rigidly connected with a plurality of spaced transverse plates 32 which are connected with the longitudinal I-beams 22. The lower platen plates 30 rest on and are connected with spaced transverse plates 33. Electric heating units 35 are mounted in heat conducting relation with the platen plates 30 and 31 in the spaces between the aforementioned supporting plates 32 and 33. Suitable thermal insulation, not shown, covers the plates 32 and 33 and the heating elements. The lower platen is flexible to some extent in both longitudinal and transverse directions and any tendency to warping is confined to the relatively narrow widths of the plates 30. The plates 30 and 31 are not directly connected to each other.

The pneumatic diaphragm units 18 each comprise a rigid bottom shell or housing member 40 having a flat bottom surface adapted to rest on the flat upper surface of an I-beam 17. A flexible diaphragm 41 is secured around its rim to a peripheral flange edge of the housing 40 to form a closed pressure chamber 42 wherein the diaphragm 41 is adapted to move vertically, like a piston, in response to variations in pneumatic pressure in the chamber 42 beneath the diaphragm. The main central area of the diaphragm 41 is reinforced by a circular metal plate 43 which supports the cylindrical struts 19. The upward thrust of each strut 19 is distributed over a plurality of the spaced plates 33 by a square cap plate 45, as best shown in Figure 6. An upper housing part 46 protects the diaphragm 41 and has a large central opening to allow free vertical movement of the strut 19. The struts 19 have portions cut away on the upper and lower ends thereof to form offset feet 47 for engaging the diaphragm plate 43 and a cap plate 45. This arrangement provides ventilation for cooling the struts and lengthens the heat conducting paths between cap plate 45 and diaphragm plate 43 so that the high platen temperature will not be transmitted directly to the diaphragm material.

Referring now to Figures 4 and 5, the several diaphragm chambers 42 are connected with three manifold pipes 50 equipped with individual valves 51 to turn on and shut off air pressure from supply pipes 52. Each valve is operated by a lever 53 which has an angular movement not exceeding 90 degrees between open and closed limit positions. The three valve levers 53 are connected together for movement in unison by a common link 54 which has one end pivotally connected with a piston rod 55 in an air cylinder 56. One end of the cylinder 56 is pivotally connected at 57 with a supporting bracket 58 on the frame of the press.

Cylinder 56 is of the double acting type having two pipe connections 61 and 62 with a conventional solenoid valve unit 63. The solenoid valve unit 63 has two coils for shifting a balanced spool valve member (not shown) to one or the other of two limit positions. In one limit position the valve admits air pressure from a supply pipe 64 to one of the supply pipes 61, 62 to move the piston rod 55 and valve levers 53 to the off or closed position. At such time the other of the two pipes 61, 62 is connected

by the spool valve member with an exhaust port 65 in the housing of the solenoid valve. In its other limit position, the spool valve member reverses the connections between pipes 61, 62 and the supply and exhaust pipes 64, 65 to move piston rod 55 in the opposite direction and shift valve levers 53 to open position.

When valve levers 53 are in closed position, the pressure in supply pipes 52 is shut off from manifold pipes 50 and the latter are connected with exhaust ports 66 to relieve the pressure in all the diaphragm chambers 42. When the pressure is thus reduced to atmospheric value, the weight of the lower platen depresses the diaphragms 41, causing the press to open. When the valve handles 53 are in open position, exhaust ports 66 are closed and supply pipes 52 are connected with manifold pipes 50 to establish sufficient pressure in diaphragm chambers 42 to lift the diaphragms 41 and close the press. In addition to supplying merely the pressure necessary to raise the lower platen to close the press, the pressure in diaphragm chambers 42 exerts sufficient additional upward force against the lower platen to press the top and bottom sheets of paper 10 and 12 against the opposite faces of core strips 11 to effect a strong permanent bond at the platen temperature which is maintained by heating units 35. By reason of its flexibility, the lower platen adjusts itself to irregularities in the thickness of the work and applies uniform pressure over the whole area of the platen.

The feed roll mechanism C and clipper D are mounted on a frame 70 which may be bolted to the frame of the press B. The frame 70 includes a pair of standards 71 supporting a transverse beam 72. The standards 71 also have bearings for the shafts 73 and 74 of longitudinal shearing cutters 75. These are rotary type cutters which trim off the rough edges and split the completed ribbon laminate into a plurality of parallel ribbons of the desired widths.

Another pair of standards 76 is equipped with bearings to support the shafts 77 of a pair of feed rolls 78. The laminate material is supported in its passage through the trimming cutters 75 and feed rolls 78 by a transversely flat surface 79 having a longitudinal arch 80 between the feed rolls and the clipper D. The function of the arch 80 is to facilitate the upward buckling of the material during the brief interval while its forward movement is arrested by the operation of the clipper knife. This prevents excessive crowding of the material against the clipper blade which might otherwise cause binding and interfere with a true and straight transverse cut.

The clipper D is of conventional construction, being of the type used to cut wood veneer. The movable blade is normally raised to allow the material to pass thereunder, and is actuated at the proper time by a piston rod 83 in a pneumatic cylinder 81 acting through a conventional toggle linkage 82.

The lower trimming cutter shaft 74 and lower feed roll shaft 77 are rotated by suitable drive mechanism from the electric motor 85, indicated diagrammatically in Figure 9. The upper trimming cutter shaft 73 is gear driven from the lower shaft 74 and the upper feed roll is similarly driven by the lower feed roll. Cutter shafts 73 and 74 are driven at a speed which will rotate the cutting rolls 75 slightly faster than the material is pulled ahead by the feed rolls 78.

Control system

The lower feed roll shaft 77 carries a small gear 86, Figure 7, which drives a larger metering gear 87 equipped with a switch actuating pin 88. As shown in Figure 2, a feed switch 90 is mounted on the frame 70 adjacent the metering gear 87 in a position to be actuated by the pin 88 once in each revolution of the metering gear 87. Feed motor 85 is deenergized by such actuation of the switch 90, but the momentum of the drive mechanism carries the pin 88 out of engagement with the switch 100 after the motor is deenergized whereby the switch 90 always re-

mains in its normal position shown in Figure 9 when the feed means comes to rest.

The transverse beam 72 carries a bearing 91 for a pivotal arm 92. Arm 92 is mounted on a stub shaft 93 to pivot in the bearing 91. The free end of arm 92 carries a pivotal support 94 for a metering wheel or disc 95 which is equipped with a plurality of apertures 96 adjacent its periphery. One or more switch actuating pins 97 may be inserted in the apertures 96. Metering wheel 95 rides on and is frictionally driven by a drive cone 98 mounted on a threaded end of the upper feed roll shaft 77. By shifting cone 98 axially on its supporting shaft 77 the wheel 95 may be brought to bear on different diameter portions of the cone as shown in Figure 7 to vary the driving ratio. Cone 98 is secured in adjusted position by a jam nut 99. Mounted on the arm 92 adjacent the metering wheel 95 is a clipper switch 100 in a position to be actuated by the pin or pins 97.

A platen switch 101 is mounted on the frame of the machine in a position to be actuated by a lug 89 on the lower platen 20, as shown in Figure 2. The operating mechanism of this switch is arranged so that the switch is not operated when the lower platen is raised. When the press opens, the descending movement of the lower platen 20 causes the switch 101 to be momentarily closed and then reopened.

A number of manual control switches are mounted on the frame of the machine adjacent the table A as shown in Figure 2. There is a toggle switch 102 which is in the nature of a main switch, a feed stop switch 103, and a press close switch 104 which will also stop the feed mechanism. The numeral 105 designates a jogging switch to operate the feed mechanism momentarily when desired.

The numerals 106 designate adjustable thermostatic controls for the platen heating units 35, whereby the platen temperatures may be maintained at certain predetermined constant values.

Figure 9 illustrates the electric and pneumatic control system for opening and closing the press B, starting and stopping the feed roll mechanism C and operating the clipper D. The heating circuits for platen heating units 35 are controlled exclusively by the thermostatic means 106 and are not shown in Figure 9. The feed motor 85 is energized from a power circuit 109 and the control system is energized from the supply wires 110, 111. The power circuit for motor 85 is controlled by a feed relay having a solenoid coil 112 and an armature 113 which is lifted to close the motor circuit when the relay is energized. At such times, a fourth contact bar 114 is held in engagement with a pair of stationary contacts 115, 116. When the relay is deenergized, the armature 113 falls to the position shown, opening the motor circuit. For convenience, this and the other relays in the system will be referred to generally by the numerals applied to their solenoid coils.

Contact 115 is connected with a wire 117 leading to a stationary contact 118 which is normally engaged by the switch arm 120 in feed switch 90. A second stationary contact 121 is momentarily engaged by the switch arm 120 during the time that switch actuating member 122 is engaged by the moving pin 88 on metering gear 87. An internal spring, not shown, in the switch 90 always returns the movable switch arm 120 into engagement with the contact 118 after pin 88 leaves engagement with actuating member 122 and motor 85 and gear 87 come to rest. Contact arm 120 is connected by a wire 123 with the supply wire 111.

The push button switches 103 and 104 are spring returned to the normal positions shown. A wire 125 connects solenoid coil 112 with a stationary contact 126 in the switch 104 which has a second stationary contact 127 in the same circuit. Contact 127 is connected with a contact 128 in the switch 103 which has a second stationary contact 129. Contact 129 is connected with the terminal 130 of toggle switch 102. The other terminal 131 of the toggle switch is connected with the line wire

110. Switch 104 also has a stationary contact 132 connected with line wire 111 and a contact 133 connected with a wire 134.

The push button switch 105 is normally spring biased to its open position shown. A stationary contact 135 is connected with wire 125 and a stationary contact 136 is connected with line wire 110. A third stationary contact 137 is connected with a wire 138 and a fourth stationary contact 139 is connected with a wire 140 leading to the line wire 111. The wire 138 is also connected with relay solenoid terminal 116 and the terminal 141 of platen switch 101. The other terminal of switch 101 is connected with a wire 142 leading to the line wire 111.

Wire 134 is connected with contact 121 in feed switch 90 and also with one terminal of the solenoid coil 145 of a valve control relay for the air supply to lift the lower platen. This relay solenoid circuit is completed through a wire 146 connected with terminal 130 of toggle switch 102. The relay has an armature 147 equipped with a contact bar 148 normally engaging a pair of stationary contacts 149 and 150 when the relay is deenergized. Contact 149 is connected with a wire 151 and contact 150 is connected with the wire 146. When the relay is energized the contact bar 148 engages a pair of contacts 152 and 153. Contact 152 is connected with a wire 154 and contact 153 is connected with the wire 146. The numeral 155 designates diagrammatically a dash pot mechanism or other time delay device to hold the relay armature in raised position for an interval of time necessary for a pressing operation. This is a conventional type of delayed opening relay which may be adjusted within the desired limits to hold the armature up after solenoid coil 145 has been deenergized.

The solenoid valve 63 in Figures 5 and 9 has a pair of opposed solenoid coils 156 and 157 connected with the respective wires 154 and 151. A common wire 158 connects the two coils with line wire 111. When the coil 156 is energized the solenoid valve 63 admits air to the proper end of cylinder 56 in Figure 5 to open the valves 51 and raise the lower platen 20, and when the coil 157 is energized the solenoid valve 63 admits air to the other end of cylinder 56 to close the valves 51 and exhaust the air in diaphragm chambers 18 through ports 66 to atmosphere to lower the platen 20 and open the press.

Clipper switch 100 has a movable contact arm 160 connected through wire 161 with line wire 111 and a stationary contact 162 connected through a wire 163 with one terminal of solenoid coil 165 of a clipper relay. Contact arm 160 remains in open circuit position until actuating member 159 is engaged by pin 97 on metering wheel 95. The other terminal of relay coil 165 is connected with wire 146. This clipper relay has an armature 166 equipped with a contact bar 167 and a delayed opening device 168. When this relay is energized the contact bar 167 engages a pair of stationary contacts 169 and 170. The delay device 168 holds the contact bar 167 in engagement with contacts 169 and 170 for a sufficient time to allow the clipper to operate once and then the contact bar is dropped back into open circuit position.

The clipper cylinder 81 is a double acting cylinder having air pressure supply pipes 171 and 172 connected with the opposite ends thereof to reciprocate the piston rod 83 in opposite directions in successive cutting strokes. The pipes 171 and 172 are connected with a solenoid valve 175 which is in turn connected with an air pressure supply pipe 176. The valve device 175 contains a balanced spool valve which is shifted between two limit positions by a pair of opposed solenoid coils 177 and 178. When coil 178 is energized, the valve connects pipe 172 with pressure supply pipe 176 and when coil 177 is energized, the pipe 171 is connected with pressure.

A wire 179 connects the two coils with relay contacts 169. The respective coils are connected individually with a pair of stationary contacts 180 and 181 in a pressure switch, designated generally by the numeral 182. Sta-

tionary contacts 183 and 184 in the pressure switch are connected with line wire 111. A contact bar 185 is connected with a flexible diaphragm 186 in a diaphragm chamber 187. A spring 188 normally deflects the diaphragm inwardly and holds the contact bar 185 in engagement with contacts 180 and 183. A pipe 186 connects diaphragm chamber 182 with the pipe 172 whereby when pressure is admitted to this pipe the diaphragm 186 is deflected outwardly, causing the contact bar 185 to engage the other pair of contacts 181 and 184. The switch device 182 thereby acts as a reversing switch for the solenoid valve 175 to admit air to opposite ends of the cylinder 81 in successive clipping operations.

Operation

In starting up the machine the lower and upper face sheets 10 and 12 are first pulled through the open press by hand and engaged between the feed rolls 78. Glue coated core strips 11 are then laid up on the table A on top of the lower sheet 10. As shown in Figure 1, the operator first places the core strips 11 on the paper 10 and then straightens and aligns them and pushes them into edge abutting relation in preparation for the first cycle of the machine.

In Figure 9 the various switches and relays are shown in their normal rest positions when the machine is shut down with all circuits deenergized. When the material is ready for operation of the machine, the operator first switches on the heating units 35 and closes toggle switch 102. This produces no immediate function but serves to prepare certain circuits for the initial phase of operation. The energization of platen valve coil 157 merely continues to hold the press open. To start the machine, the operator presses push button switch 104, closing a circuit from line wire 111 through wire 134, relay solenoid 145, wire 146, and toggle switch 102 back to line wire 110.

This circuit raises the armature of press relay 145, and after push button 104 is released the delay device 155 holds the armature 147 in raised position with contact bar 148 in engagement with contacts 152 and 153 until the end of the interval for which the device 155 is set. A circuit is thereby closed through line wire 110, toggle switch 102, wire 146, contact bar 148, wire 154, solenoid valve coil 156, and wire 158, back to line wire 111. This produces operation of solenoid valve 63 to admit air pressure to the proper end of cylinder 56 in Figures 4 and 5 to open the valves 51 and admit air pressure to the manifold pipes 50 leading to all the diaphragm chambers 18 beneath the lower platen 20.

The lower platen is thereby raised and the press held closed until time delay device 155 releases the relay armature 147 to allow it to return to the normal position shown. The dropping of armature 147 breaks the circuit through solenoid valve coil 156 and energizes solenoid valve coil 157 by a circuit through a line wire 110, toggle switch 102, wire 146, contact bar 148, wire 151, coil 157, and wire 158, back to line wire 111. The energizing of solenoid valve coil 157 shifts the spool valve member in the valve unit 63 to reverse the air supply connections to cylinder 56, moving piston rod 55 in a direction opposite to its previous movement and closing the valves 51. When the valves 51 are thus closed, the supply pressure from pipes 52 is cut off and the pressure in diaphragm chambers 18 and manifold pipes 50 is exhausted to atmosphere through valve ports 66, allowing the lower platen 20 to fall and open the press.

The closing of the press brought lug 89 into engagement with the operator of switch 101, but the switch mechanism is arranged so that no switch movement is produced by such engagement. However, when the press opens, the disengagement of lug 89 from the switch operator (Figure 2) causes switch 101 to close, completing a circuit through line wire 111, wire 142, switch 101, wire 138, relay solenoid coil 112, wire 125, push button switch 104, push button switch 103, and toggle switch 102, back

to the line wire 110. This circuit energizes feed relay 112, lifting the armature 113 and closing the power circuit from supply wires 109 to the feed motor 85. The operating mechanism (not shown) for switch 101 is arranged to cause this switch to be closed momentarily and then reopened during the descending movement of lower platen 20, whereby switch 101 immediately returns to its open position shown in Figure 9. However, the lifting of relay armature 113 completes a holding circuit for the relay through wire 123, contact arm 120 of switch 90, wire 117, and contact bar 114 in parallel with the reopened platen switch 101. This holding circuit maintains the energization of the feed motor after platen switch 101 reopens.

Motor 85, thus energized by the opening of the press, drives the feed rolls 78 to pull a length of the material through the press and push it through the clipper D. By reason of the holding circuit just described, this feed movement continues until pin 88 on gear 87 engages the operating lever 122 of feed switch 90 to shift the contact arm 120 out of engagement with contact 118 and into engagement with contact 121. Disengagement of contact arm 120 from contact 118 breaks the holding circuit for relay 112, allowing the armature 113 to drop and deenergize feed motor 85. After the motor 85 has been deenergized, the momentum of the feed drive mechanism carries the pin 88 out of engagement with switch actuating lever 122, allowing contact arm 120 to be returned by a switch spring (not shown) to its normal engagement with contact 118. However, the holding circuit for relay 112 has now been opened by the dropping of contact bar 114, so the return movement of switch arm 120 at this time is of no effect and the feed mechanism remains stationary.

The metered operation of feed rolls 78 has thus pulled the pressed length of material out of the press and has pulled in a new length of material including glue spread core strips 11 which have been laid up on the table A during the pressing interval. When contact arm 120 in feed switch 90 engages the contact 121, a circuit is completed from line wire 111 through wire 123, contact arm 120, wire 134, and platen relay 145 to wire 146, toggle switch 102, and line wire 110. This circuit energizes platen relay 145 which lifts its armature 147 to bring contact bar 148 into engagement with contacts 152 and 153. After contact arm 120 leaves engagement with contact 121, this circuit is broken but the armature 147 is held in raised position for the duration of another pressing interval by the action of the delayed opening device 155. The lifting of contact bar 148 again completes a circuit through the solenoid coil 156 of solenoid valve 63 to effect operation of the piston rod 55 and valves 51 in Figures 4 and 5 as previously described, admitting air to the diaphragm chambers 18 and closing the press for another press cycle. The press and feed cycles thus repeat in sequence until the machine is stopped by the operator.

If toggle switch 102 is opened during feed movement, the feed relay 112 is deenergized to stop the feed motor 85. If toggle switch 102 is opened during a press interval, both solenoid valve coils 156 and 157 are deenergized, but this does not result in the closing of valves 51 to open the press because the balanced spool valve member in solenoid valve 63 remains in its last position supplying air pressure to the end of cylinder 56 which opens the valves 51. Switch 102 is not used for emergency stop purposes.

Push button switch 103 serves as an emergency stop for the feed motor 85 in case the core strips 11 become disarranged on the lay-up table A or in case the operator does not have a sufficient number of core strips in position to occupy the length of the press, or for any other reason when it may be desired to stop the feed movement. The feed motor is re-started by pressing switch

104. Switch 103 does not affect the controls for the press.

Push button switch 104 stops the feed and closes the press. This switch is also used as a starting switch in the manner hereinabove described.

Push button switch 105 is referred to as a jogging switch. For example, in setting up the machine for operation, after the upper and lower sheets 10 and 12 have been drawn through the press, the ends of these sheets may be inserted in the nip of the feed rolls 78 and the jogging switch touched momentarily to rotate the feed rolls sufficiently to grip the paper. This is done while the main toggle switch 102 is open, whereby the feed relay 112 is closed and feed motor 85 is energized only so long as the switch 105 is held closed. The jogging switch 105 thereby permits operation of the feed rolls for a long or short interval, as may be desired, without putting the machine in its normal cycle of operation subject to the other automatic control devices. It will be observed that the holding circuit through contact bar 114 is ineffective to maintain the feed relay 112 energized when switch 102 is opened because release of the jogging switch 105 opens the circuit connection with supply wire 110.

The metering wheel 95 operates the clipper D at predetermined increments of feed movement without regard to the length of feed movement taking place preliminary to each press cycle. When pin 97 engages the operating lever 159 of clipper switch 100, contact arm 160 is engaged with contact 162 to close a circuit from supply wire 111 through wire 161, contact arm 160, wire 163, clipper relay solenoid coil 165, wire 146, switch 102, and supply wire 110. The energization of clipper relay 165 raises its contact bar 167 into engagement with contacts 169 and 170 to complete a circuit from wire 146 through wire 179 and one or the other of the valve solenoid coils 177 or 178 as determined by the position of the contact bar 185 of pressure switch 182. When contact bar 185 engages the upper contacts 180 and 183, the solenoid coil 178 is energized to supply pressure to the pipe 172 and retract the piston rod 83 to operate the clipper mechanism. The admission of pressure to pipe 172 operates the pressure switch 180 to deenergize the circuit for solenoid coil 178 and prepare a circuit for solenoid coil 177 to produce an opposite movement of piston rod 83 when the clipper switch 100 and relay 165 are next operated. It was previously explained that the clipper is operated by a toggle mechanism whereby the cutting blade makes one stroke when the piston rod 83 moves outwardly and another stroke when the piston rod moves inwardly.

In order to prevent repeated operations of the clipper if the pin 97 should come to rest in engagement with the operating lever 159 of clipper switch 100 at the end of a feed movement, the clipper relay 165 is equipped with a delay device 168 which causes the armature 166 to be released promptly after momentary closing of the relay contacts, even though the relay coil 165 may still be energized by the closed position of switch arm 160.

A wide variety of suitable glues are available on the market. The glue may be either of the cold setting or hot setting type, according to the speed desired in the pressing operation. Urea resin glues are preferred.

The temperature and pressing time are governed by the nature of the materials used. A thermal gradient exists through the thickness of the face sheets 10 and 12 whereby in a short press interval the temperature at the glue line may be considerably lower than the platen temperature, depending upon the thickness and heat conductivity of the sheets 10 and 12. When the sheets 10 and 12 are paper, a platen temperature of 450° F. has been used successfully with a pressing interval of 10 to 15 seconds. The feed movement requires about five seconds, thereby allowing three presses per minute. In an eight-foot press, this rate of operation produces 24 linear

feet of laminate product per minute. It is not necessary that the press interval be long enough to dry the glue completely, as it will continue to dry and set after leaving the press. The foregoing values of time, temperature and dimension are merely illustrative and are not intended to limit the invention.

Thus, the present machine is fully automatic in its press, feed and clipping operations, producing continuous ribbons of laminate product which are automatically clipped to any desired length. The press cycle is fast enough to permit a substantially continuous work flow as fast as a workman can lay up the core strips on the bottom continuous face sheet 10. It is not necessary to assemble a great amount of material for a single press load, and it is not necessary to incur a larger investment in a battery of presses to achieve a substantially continuous work flow. Also, there is considerable advantage in the very short interval of time transpiring between the spreading of the glue on the core strips and the pressing operation, as this permits the use of an inexpensive cold setting glue of a grade which cannot be used in a conventional multiple platen hot press because of the necessarily relatively long interval of time between the glue spread operation and the pressing operation.

Having now described our invention and in what manner the same may be used, what we claim as new and desire to protect by Letters Patent is:

1. A hot press for laminating sheet materials comprising a rigid horizontal platen, a flexible horizontal platen, and a plurality of pneumatic diaphragm units operatively connected with said flexible platen for vertical movement, the work engaging surface of said flexible platen comprising a plurality of flat plates disposed in edge abutting relation, a plurality of elongated narrow members connected with said plates, and a plurality of thrust means each extending across a plurality of said members and connecting said members with said diaphragm units.

2. A hot press for laminating sheet materials comprising a rigid horizontal platen, a flexible horizontal platen, and a plurality of pneumatic diaphragm units operatively connected with said flexible platen for vertical movement, the work engaging surface of said flexible platen comprising a plurality of flat plates disposed in edge abutting relation, a plurality of spaced members supporting said plates, heating units disposed in the spaces between said members, aperture tubular struts on said diaphragm units, and an individual thrust plate on each of said tubular struts engaging a plurality of said members.

3. A hot press for laminating sheet materials comprising a rigid horizontal upper platen, a lower platen support comprising a plurality of longitudinal beams, a plurality of pneumatic diaphragm units seated on each of said beams, a ventilated tubular strut on each diaphragm unit, an individual thrust plate on each of said

struts, a plurality of spaced transverse plates supported by said thrust plates, a plurality of longitudinal plates supported on said transverse plates and disposed in side by side edge abutting relation, and heating units mounted in the spaces between said transverse plates, said plates and heating units constituting a flexible lower platen for the press.

4. Apparatus for laminating sheet materials comprising a hot press having a movable platen, means for moving said platen to open and close the press, feed rolls for moving said materials through the press, means for driving said feed rolls, a feed control relay connected with said driving means, a platen control relay connected with said platen moving means, a control member rotatably driven by said feed rolls, a switch connected with both of said relays and actuated by rotation of said control member to operate said relays to stop said driving means and close the press, means to operate said platen control relay to open the press, and a switch actuated by opening movement of said platen to operate said feed control relay to start said driving means.

5. Apparatus for laminating sheet materials comprising a hot press having a movable platen, fluid pressure operated means for moving said platen to open and close the press, feed rolls for moving said materials through the press, an electrical motor for driving said feed rolls, a feed control relay controlling the energization of said motor, a platen control relay and solenoid valve controlling said fluid pressure means, a control member rotatably driven by said feed rolls, a switch controlling both of said relays and actuated by rotation of said control member to operate said relays to stop said motor and close the press, means to operate said platen control relay after a pressing interval to open the press, and a switch actuated by opening movement of said platen to operate said feed control relay to start said motor.
